ATTORNEY

UNITED STATES PATENT OFFICE.

LEO LEMM, OF MILWAUKEE, WISCONSIN, ASSIGNOR TO LULA THEIS, OF MILWAUKEE, WISCONSIN.

AIRSHIP.

Application filed July 27, 1922. Serial No. 577,812.

To all whom it may concern:

Be it known that I, LEO LEMM, a citizen of the United States, residing at Milwaukee, in the county of Milwaukee and State of Wisconsin, have invented new and useful Improvements in Airships, of which the following is a specification.

This invention relates to improvements in air ships, the general object of the invention being to provide a plurality of gas holding members with means for filling them simultaneously and with means for preventing the puncturing and the resultant escape of gas from one member from affecting the other members, thus providing buoyancy even though a number of the members have collapsed.

Another object of the invention is to provide a plurality of propellers at the sides of the ship with means for actuating the same by independent motors.

A further object of the invention is to make the rudders in sections so that if one or more sections should become damaged the ship can still be steered by the remaining sections.

A further object of the invention is to construct portions of the frame part of metal reinforced by wood so as to make the frame part of great strength and reduce the danger of the framework collapsing.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the invention.

Figure 2 is a plan view thereof.

Figure 3 is a longitudinal sectional view.

Figure 4 is a front end view.

Figure 5 is a rear end view.

Figure 6 is an enlarged fragmentary transverse sectional view. 50

Fig. 7 is an enlarged fragmentary view of a portion of the framework.

Figure 8 is a section on line 8—8 of Figure 7.

Figure 9 is a section on line 9—9 of Figure 7. 55

Figure 10 is an enlarged sectional view through the lower portion of one of the gas members and showing the check valve therefor. 60

Figure 11 is a perspective view of a portion of one of the channel bars.

Figure 12 is a similar view of one of the ring members.

Figure 13 is a detail sectional view showing the driving means for a propeller. 65

As shown in these views the vessel is divided into a plurality of compartments by the partitions 1 and each compartment contains a balloon 2. The partitions are preferably formed of resilient material or similar material to reduce friction between the partitions and the balloons and thus prevent wear of the parts. A filling pipe 3 runs along the bottom of the vessel and this filling pipe is connected with each of the balloons by the connection 4, each connection having a spring controlled check valve 5 for preventing the escape of gas from the balloon but permitting the gas to pass from the filling pipe into the balloon. The filling pipe is provided with a coupling 3' which extends through the lower part of the vessel and is adapted to be connected with a supply pipe so that the balloons can be filled with gas simultaneously. 75

The valves will prevent the gas from escaping from the balloons and it will be seen that if one balloon is punctured the gas will still remain in the other balloons and I prefer to so construct the parts that a number of these balloons can collapse and yet the vessel will retain its buoyancy through the remaining balloons. 80

The frame of the vessel is composed of a number of substantially ring-shaped members 6 and the longitudinally extending 85

members 7 which are bolted to the members 6, the framework being strengthened by the stay wires 8. I prefer to form each member 6 of a pair of angle members 9 which have 5 their abutting flanges bolted together with the partition forming material clamped between them. These members 6 are made up of a plurality of flat portions, each of which is arranged at a slight incline to the adjacent 10 portions and the portions which are bolted to the members 7 are enlarged, as at 10, so as to provide large seating surfaces for said members 7. The members 7 are composed of channel strips 11, preferably 15 formed of aluminum and wooden strips 12 which are seated in the channel strips and bolted thereto. The members 6 are also preferably formed of aluminum. The members 7 are located at the junctions of the inclined 20 portions of the members 6 and I also provide members 7' which are placed intermediate the junctions of the inclined parts, these members 7' being formed of metal and wood though in this case the wooden strips 25 12' project a considerable distance above the metal strips. The envelope or cover 13 is fastened to the wooden strips. The cabins or gondolas 14 are connected by the passageways 15, the fore and aft gondolas containing 30 the motors and the central gondola containing the steering mechanism.

I prefer to place two propellers 16 at each side of the vessel, these propellers having four blades each. They are carried by frames 17 which are connected with the framework of the vessel and each propeller has its shaft geared to a drive shaft 18 which passes downwardly at an incline into a gondola 14 where it is suitably connected 35 with a motor 19. I provide a motor, preferably of twelve cylinders, for driving each propeller so that they are driven independently of each other. The gears 20 which connect the drive shaft with the propeller shaft are enclosed in a casing 21 which is carried by the framework 17.

The vertical rudder is formed in sections, as shown at 22. These sections are rotatably mounted on a shaft 23 supported at the 40 rear end of the vessel by the projecting framework 24. A rock shaft 25 is arranged in the rear end of the vessel and said shaft has arms 26 thereon which are connected by the flexible members 27 with the arms 28 on the rudder sections. This shaft 25 is rocked by the movement of the steering wheel 29 in the central cabin through the connections 30 which are fastened to the said shaft. In this way if anything should 45 happen to one or more sections the remaining section or sections can be used to steer the vessel.

The horizontal rudders 31 are connected by the link 32 and the arms 33 on these 50 rudders are connected by the flexible mem-

bers 34 with the arms 35 of the rock shaft 36. This rock shaft is connected by the flexible members 37 with the steering wheel 38 in the central cabin.

From the foregoing it will be seen that 70 the balloonets are filled simultaneously and that the valves will hold them inflated. By using a plurality of these balloonets there is no danger of the ship falling unless most of the balloonets have been punctured. For 75 instance, if the ship contains ten balloonets, five of them may be punctured and yet the ship will remain afloat through the buoyancy imparted to it by the undamaged balloonets. By placing the balloonets in the 80 compartments, the walls of which are formed of non-frictional material wear on the fabric of the balloonets is prevented and the balloonets are held against movement. The propellers arranged and constructed 85 as shown will drive the ship at great speed and the ship can be maneuvered by these propellers, in addition to the rudders, as they are driven from separate motors. The construction of the framework imparts 90 great strength and rigidity to the ship for if the metal should break the wooden parts would still hold and vice versa. The passageways permit the crew to pass from one 95 gondola or cabin to another without being subjected to the elements and these passageways may be connected with the interior of the vessel by the ports which are closed by the doors 40. The rudders being constructed 100 in sections will permit the ship to be guided even though some of the sections have been damaged and put out of action.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. An aircraft comprising a body, gas holding means therein, a cabin adjacent each end of the body and at the lower part of the same, a central cabin, passages connecting the cabins together, propellers at the sides of the body, motors in the end cabins, means for connecting the motors with the propellers, steering means at one end of the body and actuating means for the steering means arranged in the central cabin.

2. In an aircraft, a framework constructed of substantially ring-shaped members, each formed of a pair of members of angle shape 115 in cross section with their adjacent flanges bolted together, horizontally extending members fastened to the ring-shaped members, some of the horizontal members being 120 formed of channel-shaped metal pieces and 125 130

wooden strips located in the channels and fastened therein.

3. In an air ship, a body comprising a framework consisting of substantially ring-shaped members and longitudinally extending members secured to the ring-shaped members, each ring-shaped member being formed of two parts bolted together and

partitions dividing the body into compartments, the partitions being clamped between the parts of the ring-shaped members. 10

In testimony whereof I affix my signature.

LEO LEMM.
